UNITED STATES PATENT OFFICE

1,941,729

MAGAZINE ADJUSTING DEVICE FOR TYPOGRAPHICAL COMPOSING MACHINES

Christian Augustus Albrecht, Berlin, Germany,
assignor to Mergenthaler Linotype Company,
Brooklyn, N. Y., a company of New York

Application May 25, 1932, Serial No. 613,401, and
in Germany May 27, 1931

9 Claims. (Cl. 199—20)

In typographical composing machines, having a plurality of magazines it has already been proposed to raise and lower the magazines to adjust them to their respective operative positions, by means of cams which are actuated by a crank handle or lever located in proximity to the keyboard. In cases involving a considerable range of adjustment and consequently a considerable throw of the cams transmitting gear has been employed, preferably a bevel gear, and the shaft of the cam disc extending in the longitudinal direction of the machine has been rotated by a crank handle, actuated in a plane parallel with the front of the machine both for effecting a change 10 of magazines in the operative position, and for elevating the magazines beyond the operative position for the purpose of removing them from the machine.

According to the invention, two independently operated mechanisms are provided for controlling the cam shaft, to be employed respectively for shifting the magazines in the operative position and for elevating the magazines beyond the operative position, at least one of these mechanisms being actuated by a simple fore-and-aft movement of a lever located in the vicinity of the keyboard of the machine whereby the operation is simplified without providing, as has heretofore been proposed, separate devices for engagement with the machine frame for effecting the raising of the magazines beyond their operative position.

In the accompanying drawing, two constructional forms of the invention have been illustrated. In the said drawing:

Figure 1 is a side elevation of sufficient of a composing machine to illustrate the application thereto of one constructional form of the invention;

Figure 2 is an elevation, partly in section, as viewed from the right-hand side of Figure 1;

Figure 3 is an elevation, partly in section, corresponding to the left-hand portion of Figure 2, showing a modified constructional form, and

Figure 4 is an elevation of the lever mechanism as viewed from the right-hand side of Figure 3.

In the constructional form of machine illustrated by way of example, there are provided two magazines a, a' , which are supported on a frame b , which is adapted to rock about a pivot (not shown) located at its upper end for effecting the adjustment of the lower ends of the magazines relatively to the assembler entrance n . The frame b is provided at its lower extremity with a

lug or projection c , which carries a roller adapted to run in the groove of a cam disc d .

The cam disc d , is mounted upon a shaft e , supported in the machine frame f . One end of the shaft e , extends beyond the adjacent part 60 of the machine frame, and is supported loosely in a bush or sleeve g , which is located between the shaft and its bearing. This sleeve g , on its outer end, is provided with a clutch member adapted to be engaged with a co-operating clutch 65 member on the adjacent hub of a hand wheel h feathered on the outer end of the shaft e . The hand wheel h is thus not rotatable independently of the shaft e ; but is axially movable thereon for the purpose of being coupled with and uncoupled from the sleeve g . To the sleeve g is rigidly secured a boss k , provided with two arms i, i' . The arms i are connected with the escapement rods by means, not shown in the drawing, which effect the disengagement of said rods 70 from the escapement mechanisms during the movement of the magazines, whilst the arm i' is connected to a lever n by means of a link m , the said lever being adapted to rock about a stationary axis o on the machine frame, and being 75 also provided with a handle p . Pivotedly connected to the magazine frame b , are two bars q, q' , each provided with an adjustable collar r, r' . Two counterbalance springs t, t' , are each adapted to bear at one end against the respective collar and at the other end against a lug or boss s, s' , which latter are provided with openings for guiding the bars q, q' .

The bush g is normally coupled with the shaft e through the clutch connection with the hand wheel h as shown in Figure 2. Hence, when the lever n is swung from one to another of the two positions shown respectively in full and dotted lines in Figure 1, the shaft e will be rocked and the cam disc d , mounted thereon will raise or 90 lower the magazine column, in order to bring one of the magazines a, a' into the correct operative position relatively to the assembler entrance u . During this movement, and in the customary manner, the escapement rods will 95 simultaneously be brought out of engagement with the escapement mechanisms of the magazines by the arm i .

In order to maintain the device in its two terminal positions any preferred stops, detents 105 or the like, not represented in the drawing can be used.

In order to raise the magazine column beyond its operative position, so that the lower magazine, for example, can be removed from the ma- 110

chine, the hand wheel h is drawn outwardly along the shaft e in order to uncouple it from the bush g , and then turned so as to also turn the shaft e and the cam d without affecting the hand lever p and associated mechanism.

When the portion of the cam indicated by the dotted circle v in Figure 1 comes into engagement with the roller c^1 , the magazine column occupies its highest position, and the magazine can be removed. The dotted circle v^1 indicates the portion of the cam d which engages the roller c^1 when the upper magazine is adjusted to operative relationship with the assembler entrance u .

The alternative constructional form of the invention illustrated in Figures 3 and 4 may be conveniently employed to obviate the necessity of the operator leaving his seat at the front of the machine when effecting the elevation of the magazines beyond their operative position, and also in cases where the machine is provided with auxiliary magazines occupying the space which otherwise would be available at the side of the main magazines for access to the hand wheel h .

In the said constructional form, a hand lever x extending into close proximity with the keyboard, is substituted for the hand wheel h , and the connections next to be described are provided for enabling the said hand lever to be operated independently of the hand lever p which latter is employed, as in the before described construction, for effecting the adjustment of the magazines in their operative positions.

The hand lever x is pivoted upon the shaft e , and in order to prevent displacement of the lever axially of the shaft, a pin in the hub of the lever engages an annular groove e^1 in the shaft. Between the hub of the lever x and the adjacent face of the bush g , the shaft e carries a grooved collar w which is feathered to the shaft and is provided with a pin w^1 one end of which is adapted to engage a recess in the face of the bush g , and the other end of which is adapted to engage with a recess x^1 on the inner face of the hub of the lever x . The annular groove of the collar w is engaged by a fork y pivotally mounted at y^1 on the hand lever x .

The fork y constitutes one arm of a lever whose other arm y^2 is pivotally connected to a rod z slidably mounted in a longitudinal recess in the hand lever x . The rod z is encircled by a spring z^1 which acts between a shoulder z^3 on the rod and a web z^4 in the hand lever x , through which web the rod z passes. The lower end of the rod z is fitted with a finger grip z^2 which extends through an aperture in the lever x in close proximity to the handle x^2 of the said lever. The spring z^1 constantly tends to hold the collar w in the position shown in Figure 3, with the pin w^1 in engagement with the recess in the bush g . As the bush g is thus normally coupled with the shaft e the shifting of the magazines into their respective operative positions may be effected by the manipulation of the handle p as in the construction illustrated in Figures 1 and 2.

When it is desired to elevate the magazines beyond their uppermost operative position, the handle x^2 is grasped and with one finger the grip z^2 is brought down against it. Consequently, the ring w will be moved towards the left, as viewed in Figure 3, against the action of the spring z^1 so that the bush g will be uncoupled from the shaft e ; on the other hand, the pin w^1 will be engaged with the recess x^1 of the lever x , so as to couple that lever with the shaft e . When the lever x is then swung, the magazines will be

elevated beyond their uppermost operative positions.

It is to be understood that the constructional forms of the invention hereinbefore described and illustrated in the accompanying drawing are taken as convenient examples, and that various modifications may be made without departing from the scope of the invention. For instance, if it is desired to apply the invention to a machine in which the magazines are raised and lowered in a direction perpendicular to their plane of inclination, one or more additional rollers c^1 may be provided on the magazine supporting frame b to engage with a corresponding plurality of simultaneously actuated cams d . Further, the lever n for effecting the adjustment of the magazines in their operative position, may be replaced by a rectilinearly movable member having appropriate connections with the shaft e , and any suitable coupling devices may be employed for the connection and disconnection of the bush g and the hand wheel h or lever x . The invention is therefore not limited to any specific form or embodiment except in so far as such limitations are specified in the claims.

Having described my invention, I declare that what I claim and desire to secure by Letters Patent is:—

1. In a typographical composing machine, the combination of a plurality of magazines, a shaft and a cam thereon operable to adjust the magazines to their respective operative positions, conjointly operable means for actuating the shaft for said adjustment, and a clutch whereby one of said actuating means may be coupled with or disconnected from the shaft at will to permit the operation of the other actuating means singly for effecting the adjustment of the magazines beyond their operative positions.

2. In a typographical composing machine the combination of a plurality of magazines, a shaft and a cam thereon operable to adjust the magazines to their respective operative positions, a hand wheel for actuating the shaft to adjust the magazines beyond their operative position said hand wheel being angularly fast and axially movable on said shaft, a sleeve loosely mounted on said shaft, a lever for rotating said sleeve, and a clutch rendered operative by axial movement of the hand wheel to connect said sleeve to the shaft for effecting adjustment of the magazines to their respective operative positions.

3. In a typographical composing machine the combination of a plurality of magazines, a shaft and a cam thereon operable to adjust the magazines to their respective operative positions, a sleeve loosely mounted on said shaft, a lever for rotating said sleeve, a hand lever angularly movable and axially fast on said shaft, a clutch member axially movable on the shaft between the hub of the hand lever and the sleeve and means carried by the hand lever for adjusting said clutch member into engagement with the hub of the hand lever for adjusting the magazines beyond their operative position or with the sleeve for adjusting the magazines to their respective operative positions.

4. In a typographical composing machine the combination of a plurality of magazines, a shaft and a cam thereon operable to adjust the magazines to their respective operative positions, a sleeve loosely mounted on said shaft, a lever for rotating said sleeve, a hand lever angularly movable and axially fast on said shaft, a clutch member axially movable on the shaft between

the hub of the hand lever and the sleeve, a spring normally maintaining said clutch member in engagement with the sleeve and means carried by the hand lever for adjusting said clutch member into engagement with the hub of the lever against the action of the spring.

5. In a typographical composing machine, the combination of a plurality of magazines, a shaft and a cam thereon operable to adjust the magazines to their respective operative positions, a sleeve loosely mounted on said shaft, a lever for rotating said sleeve, a hand lever angularly movable and axially fast on said shaft, an annularly grooved collar axially movable on the shaft between the hub of the hand lever and the sleeve, means on the collar for coupling it either to the hub of the hand lever or to the sleeve, a forked lever pivotally mounted on the hand lever and engaging the grooved collar, a spring acting on said forked lever and adapted normally to maintain the collar coupled to the sleeve, and means carried by the hand lever for adjusting the forked lever to uncouple the collar from the sleeve and couple it with the hub of the hand lever.

25. 6. In a typographical composing machine, the combination of a plurality of magazines movable into and out of their respective operative positions and movable beyond said operative positions, a single element associated with the magazines and adapted to be actuated to effect the different movements thereof, and a plurality of means operable at different times for actuating said element.

7. In a typographical composing machine, the combination of a plurality of magazines movable into and out of their respective operative positions and movable beyond said operative positions, and a single element operable successively by two different actuating means to effect said movements.

8. In a typographical composing machine, the combination of a plurality of magazines movable into and out of their respective operative positions and movable beyond said operative positions, and a single element operable successively by two different actuating means to effect said movements, said actuating means being operable jointly to effect the movement of the magazines into and out of their operative positions, and one of said actuating means being operable singly to effect the continued movement of the magazines beyond their operative positions.

9. In a typographical composing machine, the combination of a plurality of magazines, a shaft and a cam thereon operable to adjust the magazines to their respective operative positions, conjointly operable means connected with the shaft for actuating the same to effect said adjustment, and means whereby one of said actuating means may be disconnected from the shaft at will to permit continued actuation of the shaft by the other actuating means to move the magazines beyond their operative positions.
